(57) CLAIM

The ornamental design for a portion of a midsole periphery, as shown and described.

DESCRIPTION

FIG. 1 is a front perspective view of a portion of a midsole periphery showing my new design;

FIG. 2 is a rear perspective view thereof; and,

FIG. 3 is a side view thereof.

The broken lines immediately adjacent to the shaded area represent an unclaimed boundary of the design. The broken line showing of the remainder of the shoe is for illustrative purposes only and forms no part of the claimed design.
